UNITED STATES PATENT OFFICE.

ALBERT KONETZNY, OF NEW YORK, N. Y.

REFLECTOR-SUPPORT FOR CANDLES.

SPECIFICATION forming part of Letters Patent No. 298,478, dated May 13, 1884.

Application filed October 4, 1883. (No model.)

To all whom it may concern:

Be it known that I, ALBERT KONETZNY, of the city, county, and State of New York, have invented a new and useful Improvement in 5 Supports for Candle-Reflectors; and I do hereby declare that the following is a full and exact description thereof, reference being had to the accompanying drawing, and to the letters of reference marked thereon, making a part of 10 this specification.

My invention relates to a cheap convenient device for supporting a reflector upon a candle, which, as the candle burns away, will maintain its position automatically, and which, 15 although it admits of use with any candle, is especially designed for the small candles adapted for the decoration of Christmas trees.

It consists in the combination, with a collar adapted to inclose and rest upon the upper 20 end of the candle, of a reflector to be carried by it, and which is fitted to direct and diffuse the rays of light, and of a counterpoise-weight serving to maintain properly the equilibrium of the collar as the candle melts away within it.

It consists, also, in the combination, with the reflector and the collar, of a handle secured to the latter, adapted either to counterbalance the weight of the reflector, or to serve 30 otherwise, in connection with a spring-actuated socket or sustaining-loop, as a support for the candle.

The accompanying drawing illustrates in perspective a candle secured upon the limb of a Christmas tree and fitted with my improved 35 device.

A represents the candle, which may be of any size or description, and which, as shown in the figure, is supported in a socket, S, 40 adapted for attachment to the branches of a Christmas tree, or which may be placed in a suitable candlestick of any form.

B represents a metallic collar adapted to fit upon the upper end of the candle, and which is made of a slightly conical or tapering form, or with an inwardly-beveled edge at its upper end, to engage and bear upon the edge or rim of the candle and to project slightly above it. The collar, when placed upon the candle, forms an annular rim about the end thereof, which 45 serves as a cup to hold the melted wax about the wick when the candle is burning and to prevent it from running down its sides and dropping therefrom upon the floor beneath.

C is a simple reflector, of metal or glass, attached to the collar B by means of an arm or wire, D, so as to be properly supported thereby in position to reflect the rays of light from the burning wick of the candle. The weight of the reflector is counterbalanced, to prevent 50 it from tipping the supporting-collar B as the candle burns, by means of a coiled or bent wire, E, or a plate of suitable form as its equivalent, secured to the collar at a point diametrically opposite the point of attachment 55 of the wire D, and which is adapted not only as a counterpoise, but as a handle for the collar and reflector.

I claim as my invention—

As a new article of manufacture, a metallic 70 collar adapted to encircle and rest upon the upper end of a candle, and fitted with a reflector attached to one side, and a counterpoise-handle attached to the opposite side thereof, substantially in the manner and for the purpose herein set forth.

In testimony whereof I have signed my name to this specification in the presence of two subscribing witnesses.

ALBERT KONETZNY.
